(57) **CLAIM**

The ornamental design for a mounting part with ornamental feature, as shown and described.

DESCRIPTION

FIG. 1 is a top perspective view of a mounting part with ornamental feature;

FIG. 2 is a top view of the mounting part with ornamental feature of FIG. 1;

FIG. 3 is a bottom view of the mounting part with ornamental feature of FIG. 1;

FIG. 4 is a right side view of the mounting part with ornamental feature of FIG. 1;

FIG. 5 is a left side view of the mounting part with ornamental feature of FIG. 1;

FIG. 6 is a front view of the mounting part with ornamental feature of FIG. 1; and,

FIG. 7 is a rear view of the mounting part with ornamental feature of FIG. 1.

The broken lines show portions of the mounting part with ornamental feature that form no part of the claimed design.
